CARBURETOR SYNCHRONIZING DEVICE

Edward E. Brush, College Station, Tex.

Application May 11, 1954, Serial No. 428,993

4 Claims. (Cl. 73—118)

The present invention relates to carburetor synchronizing devices. More particularly, it relates to a carburetor synchronizing device for quickly and accurately synchronizing the throttle settings of two or more carburetors installed on internal combustion engines.

It is among the objects of the present invention to provide a synchronizing device for multiple carburetors installed on internal combustion engines which may quickly be attached to the carburetors and in which the throttle settings of multiple carburetors may quickly and accurately be synchronized.

It is yet a further object of the present invention to provide such a synchronizing device for synchronizing multiple carburetors by which very rapid visual and precise indication of relative throttle positions in multiple carburetors may be obtained and synchronized by directly comparing the entering air velocities of the carburetors.

Yet a further object of the present invention is the provision of a very rapid visual and precise means for adjusting throttle positions of two or more carburetors.

A further object of the present invention is the provision of a very rapid visual means for synchronizing the throttle settings of more than two identical carburetors by matching them in overlapping pairs.

It is yet a further object of the present invention to provide such a carburetor synchronizing device which is inexpensive to construct and maintain, which is accurate and dependable in operation, and by which precise readings may be obtained in a minimum of time.

Other and further objects and features of the invention will be apparent from the following description of an example of the invention, given for the purpose of disclosure, taken in conjunction with the accompanying drawing, in which like character references designate like parts throughout the several views, and where:

Figure 1 illustrates a synchronizing device for carburetors constructed according to the invention and shown in front elevation attached to a pair of carburetors.

Figure 2 is a cross-sectional view taken along the line 2—2 of Figure 1, looking in the direction of the arrows,

Figure 3 is a sectional view taken along the line 3—3 of Figure 1 and looking in the direction of the arrows, and

Figure 4 is a fragmentary front elevation illustrating a different manner of supporting the manometer when in use.

Throughout the specification the terms "synchronization" and "synchronize" are used to designate that the respective throttle settings are adjusted so that these settings provide equal air flow in the respective carburetors.

Referring now to the drawing, a pair of matched venturi tubes 10 are secured to a pair of carburetors 12 to be synchronized which have had their respective air cleaners and air cleaner manifolds previously removed. While the venturi tubes may be secured in any desired manner to the air intakes of the carburetors 12, this may be accomplished by means of the plates 14 being provided with the bosses 16 projecting rearwardly therefrom, which are

2

positioned in the air intakes 18 of the carburetors 12. For attachment of the venturi tubes 10 to the carburetors 12, the bosses 16 may be provided with a plastic or resilient packing material 20 so that they fit snugly in the air intakes 18 in the carburetors 12. In securing the venturi tubes 10 to the carburetors 12, it may be necessary to place a sleeve (not shown) over the exposed ends of the carburetors, such as a rubber pipe, so that the bosses 16 may be inserted in the air intakes, such as where a butterfly valve and the like would prevent this insertion. The throats 22 of the venturi tubes 10 are thus maintained in alignment with the air intakes of the carburetors 12 and all air passing or drawn into the carburetors 12 must pass through the throats 22 of each venturi tube 10.

While reference is made to the venturi tubes 10, it will be understood that the expansion cones 23 may be eliminated and, hence, contracting nozzles are suitable without the expansion cones and the operation is the same for both.

It will be understood, of course, that the venturi tubes 10 may be secured to the carburetors 12 in any satisfactory manner; however, the arrangement described is presently preferred in view of the rapidity by which they may be secured to the carburetors and their efficiency in snugly holding the venturi throats 22 in the air intakes 18 of the carburetors so that all of the air drawn into the carburetors 12 passes through the throats 22 of the venturi tubes 10.

30 A tube like projection 24 extends upwardly from each venturi tube 10 and has a passageway 26 extending into the throat 22 of each venturi tube 10. Secured to the upper ends of the tube like projections 24 are the flexible tubes or conduits 28, which may be formed of any suitable flexible material, such as rubber and the like, which tubes have their other ends secured to the upstanding ends of opposite legs 29 of the U-shaped manometer tube 30. Thus, a difference in fluid level in the manometer legs 29 will be apparent if the air velocity in one venturi tube 10 is different from that in the other.

The U-shaped manometer tube 30 is disposed on a manometer plate 32 which has the parallel or horizontal scribe lines 34 so that the fluid level in the legs 29 of the manometer 30 may visually and readily be adjusted 45 to the same height in each manometer leg 29.

The manometer 30 and manometer plate 32 may be secured to or disposed with respect to the motor in any desired or satisfactory manner; however, it is advantageous to provide an extension 36 of the manometer plate 32 which may be provided with an aperture through which a wing nut assembly 38 extends so that the manometer plate may adjustably be secured to the face plates 14 of one of the venturi tubes 10. Thus, after the face plates 14 are attached to the carburetors 12, by merely loosening the wing nut 38, the manometer plate 32 may be adjusted into a substantially vertical position and the wing nut 38 tightened so that accurate adjustments may be made. Figure 4 illustrates the manometer plate 32 connected to a structural element of the motor 39 and, if desired, a simple clip may be substituted for the wing nut assembly 38 and projection 36 so that the manometer may be attached as desired, although any means of attachment may be omitted.

It is noted that a venturi tube produces an increase in air velocity at its throat and a decrease in static pressure. The static pressure in the throat is a function of the square of the entering air velocity and is thus a very sensitive index of air velocity and permits of extremely accurate adjustments.

70 To adjust the throttle settings of a pair or more of carburetors according to the invention, the air cleaner and air cleaner manifolds are removed from the carbure-

tors 12 and the bosses 16 may be inserted in the air intakes of the carburetors 12 by means of the arrangement described. The wing nut 38 may be loosened, if necessary, and the manometer 32 adjusted to level. As mentioned previously, the venturi tubes are matched and adjusted in manufacture so that air flow of a given velocity produces the same static pressure in the throat 22 of each venturi tube 10.

With the engine operating at idling speed and the throttle interconnect clamp (not shown) released, a difference in fluid level in the manometer legs 29 will be apparent if the air velocity in one venturi tube is different from that in the other inasmuch as the venturi tubes 10 are connected to opposite legs 29 of the manometer 30 by means of the tubes 28. Adjustment of the throttle stop screws (not shown) on the two carburetors will vary the throttling and thus the air velocity through the venturi tubes 10 into the carburetors. If the liquid level in the two manometer legs is not equal, one or both of the respective throttle screws may be adjusted until this level is equal, at which time the air velocity through the throats 22 of the venturi tubes 10 is the same and the throttle settings are synchronized. The throttle shafts (not shown) may then be interconnected to the throttle interconnect clamp with the assurance that the throttles will be synchronized in all positions. The synchronizing device may then be removed from the carburetors 12 by merely pulling outwardly on the venturi face plates 14 and, in the event there are additional carburetors to be synchronized, one of the face plates 14 may be removed from a carburetor 12 and attached to another carburetor, the additional carburetor adjusted by adjusting its throttle stop screws so that the liquid level in the manometer legs 29 is level in the manner mentioned. The throttle shaft of this third carburetor may then be interconnected with the throttle interconnect clamp as previously explained. This, of course, may be repeated as many times as desired, that is, synchronizing the throttle settings of more than two identical carburetors by matching them in overlapping pairs and utilizing one or other of the synchronized carburetors as the reference for the throttle adjustment of the others. After the desired adjustment or adjustments have been made, the air cleaner and air cleaner manifold may be attached to each carburetor.

Thus, one each of a pair of matched venturi tubes or contracting nozzles are secured to the intake of a pair of carburetors, the throats of the venturi tubes being in fluid communication with opposite legs of a U-shaped manometer, and the throttle settings of at least one of the carburetors are adjusted until the liquid level of the manometer is even. If more than two carburetors are to be synchronized, one of the venturi tubes or contracting nozzles may be secured as mentioned to a third carburetor and the throttle setting of the third carburetor adjusted until the liquid is level in the manometer. This, of course, may be repeated as often as desired by then moving either of the venturi tubes.

The present invention, therefore, is well suited to carry out the objects and attain the advantages mentioned, as well as others inherent therein.

While a single example of the invention has been given for the purpose of disclosure, numerous changes in details, rearrangements of parts and steps may be made which will suggest themselves to those skilled in the art and which are encompassed within the spirit of the invention and the scope of the appended claims.

What is claimed is:

1. A device for synchronizing the throttle adjustments of two or more carburetors comprising, a pair of matched venturi tubes, means by which one each of the venturi tubes may be secured in an air intake of each of said carburetors so that air drawn into the carburetors passes through the venturi tube secured thereto, a U-shaped manometer, means connecting a throat of each venturi tube to a different leg of the manometer so that the ratio of air passing through the venturi tubes is visibly indicated by the manometer whereby adjustment of one or more of the throttle settings of the carburetors until the liquid level in the manometer legs is equal synchronizes the throttle settings of said carburetors.
- 15 2. A device for synchronizing the throttle adjustments of two or more carburetors comprising, a pair of matched venturi tubes, a first projection extending from each tube adapted to snugly fit in an air intake of each carburetor whereby one each of the venturi tubes may be secured to one each of the carburetors and air drawn into the carburetors passes through the venturi tube secured thereto, a second projection extending upwardly from each venturi tube and having a passage extending into the throat of each venturi tube, a U-shaped manometer, flexible tubes connecting each said second projection to a different leg of the manometer so that the ratio of air passing through the venturi tubes is visibly indicated by the manometer whereby adjustment of one or more of the throttle settings of the carburetors until the liquid level in the manometer legs is equal synchronizes the throttle settings of said carburetors.
- 20 3. The device of claim 2 in which the first projection is provided with resilient packing which resiliently engages the air intake for rapid sealing attachment and detachment of the venturi tubes thereto.
- 25 4. A device for synchronizing the throttle adjustments of two or more carburetors comprising, a pair of matched venturi tubes each having a face plate thereon, a hollow boss extending from one each of said venturi tubes, said boss adapted to be inserted into the air intake of one each of said carburetors for securing one each of the venturi tubes to one each of the carburetors so that air drawn into the carburetors passes through its respective venturi tube, a manometer face plate provided with scribe lines,
- 30 45 5. A U-shaped manometer secured to the manometer face plate, means for adjustably securing the manometer plate to one of the venturi face plates, a projection extending upwardly from each venturi tube, each projection provided with a passage extending into the throat thereof, and flexible conduits attached to each of the projections and having their other ends attached to the upstanding free extremities of each leg of the manometer whereby the ratio of air passing through the venturi tubes is visibly indicated by liquid level in the manometer tubes, adjustment of one or more of the throttle settings of the carburetors until the liquid level therein is equal synchronizing the throttle settings of said carburetors.
